US00D766300S

(12) **United States Design Patent** (10) Patent No.: **US D766,300 S**
Sin et al. (45) Date of Patent: **** Sep. 13, 2016**

(54) **DISPLAY SCREEN OR PORTION THEREOF WITH GRAPHICAL USER INTERFACE**

(71) Applicant: **Samsung Electronics Co., Ltd.**, Suwon-si (KR)

(72) Inventors: **Sunho Sin**, Seoul (KR); **Ho Kim**, Seoul (KR); **Dongjin Eun**, Bucheon-si (KR); **Hyungdo Lee**, Seoul (KR)

(73) Assignee: **SAMSUNG ELECTRONICS CO., LTD.**, Suwon-Si (KR)

(**) Term: **15 Years**

(21) Appl. No.: **29/531,568**

(22) Filed: **Jun. 26, 2015**

(30) **Foreign Application Priority Data**

Feb. 27, 2015 (KR) 30-2015-0010384

(51) LOC (10) Cl. **14-04**

(52) U.S. Cl.

USPC **D14/486**; D14/492; D14/493

(58) **Field of Classification Search**

USPC D14/485-495

CPC ... G06T 13/80; G06T 15/02; G06F 15/0266; G06Q 10/06; G06Q 10/109

See application file for complete search history.

(57) **CLAIM**

The ornamental design for a display screen or portion thereof with graphical user interface, as shown and described.

DESCRIPTION

The FIGURE is a front view of a display screen or portion thereof with graphical user interface showing our new design.

The broken lines around the FIGURE show a display screen or portion thereof and the broken lines within the FIGURE show unclaimed portions of the graphical user interface; the broken lines form no part of the claimed design.

1 Claim, 1 Drawing Sheet
